Patented Feb. 26, 1924.

UNITED STATES PATENT OFFICE.

EDWIN C. WOLFE, OF CORRAL, IDAHO.

REVERSIBLE PUMP OIL CAN.

Application filed March 16, 1923. Serial No. 625,523.

To all whom it may concern:

Be it known that I, EDWIN C. WOLFE, a citizen of the United States, residing at Corral, in the county of Camas and State 5 of Idaho, have invented certain new and useful Improvements in a Reversible Pump Oil Can, of which the following is a specification.

This invention relates to improvements in 10 oil cans, particularly to the type known as a pump oil can and has for its prime object to provide a pump oil can which can be operated from any position.

A further object of my invention is to 15 provide an oil can of the above indicated character which is entirely automatic in operation, simple in construction in that same is composed of relatively few parts and so arranged that the can can be easily and 20 quickly disassembled for the purpose of repair or replacing with new parts as the case may require, and one that can be manufactured and placed on sale at a relatively low cost.

25 These and like objects of the invention will be better understood as the description follows and as is specifically pointed out in the appended claims.

Referring to the accompanying drawings 30 which form a part of this specification and which clearly illustrate the construction and operation of my improved oil can,

Figure 1 is a side elevation partly in section of an oil can constructed in accordance 35 with my invention.

Figure 2 is a similar view with a portion 40 of the spout broken away, showing the oil can in a horizontal position, and

Figure 3 is a similar view, showing the oil 45 can in an inverted position.

Referring to the accompanying drawings in detail, like characters will be used to designate like parts in the different views.

In the drawings, the numeral 1 indicates 50 the body or oil receiving chamber of my improved pump can. The body 1 is provided with a bottom 2 and a hand grip 3 attached to one side of same. In order to fill the receptacle or body 1, a removable cover 4 is 55 provided which has a finger or thumb grip 5 attached to the top of same, right above the hand grip 3. It is to be understood that if so desired, the cover 4 can be formed integral with the body 1 and a cap screw positioned at any desired point on the cover 4 for filling the chamber 1.

The cover 4 is provided with a central opening through which projects a neck portion 6. The neck extends downwardly within the chamber 1 and is bent at right angles as at 7. A pair of tubes 8 and 9, which are arranged in the form of the letter V are formed integral with the right angle portion 7, and each of the tubes are provided with a stop pin 10 at a point adjacent the right angle bend 7, and each of the stops is provided with a central opening and ball valve seat 11. The free end of each of the tubes 8 and 9 is covered by a fine wire mesh 12, for retaining in each of the tubes a ball valve 13. The upper end of the neck which projects through the central opening in the cover 4 is provided with external screw threads as at 14 for receiving thereon a 75 spout 15.

A cylinder 16 is welded or secured in any way to one side of the neck 6 at a point just above the cover 4 and the cylinder 16 has communication with the interior of the neck through an opening 17 formed in the neck. 80 A piston or plunger 18 is mounted in the cylinder 16 and works against the tension of a coil spring 19 by exerting pressure against the plunger or piston button 20.

Positioned within the neck at a point above 85 and below the opening 17 are ball valves 21 and 22, each of which is adapted to be held against their respective valve seats 23 and 24 by coil springs 25.

When the oil can is being used in the position indicated in Figure 1, which is an upright position, the piston 18 is forced inwardly in the cylinder 16 against the tension of the coil spring 19, and then allowed to return to its original position by releasing the pressure against the button 20. As the piston 18 retracts within the cylinder, the ball valve 21 is raised off of its seat against the spring 25 by means of suction, which withdraws the oil from the chamber 1 90 through the tube 8 into the compartment of the neck adjacent the cylinder and upon again operating pressure on the button 20, the oil forces the ball valve 22 off of its seat and discharges the oil through the spout 15. 105

When the oil can is used in a horizontal position, the operation of the plunger is the same as described in Figure 1, and the oil within the chamber 1 is drawn through both tubes 8 and 9.

When using the pump can in an inverted position, the oil is drawn through the tube 9

by operating the plunger in the manner above described.

In view of the foregoing description of my invention taken in connection with the accompanying drawings, it is thought that any further explanation as to the construction, operation, and objects of same is unnecessary.

While I have shown and described the preferred form of my oil can, I realize that various minor changes may be resorted to, without departing from the spirit and scope of the invention as claimed, and therefore, I do not wish to limit myself to the exact details of construction shown, nor to the combination and arrangement of parts.

What I claim as new and desire to secure by Letters Patent is:

1. In an oil can, comprising an oil receiving chamber, a cover for said chamber, a neck portion adapted to extend through said cover and being provided with an extension extending downwardly within the oil chamber and being bent at right angles, pipes secured to the right angle bend and extending in opposite directions and terminating adjacent the top and bottom of the chamber and near the side wall thereof, a ball valve positioned in each of the pipes, neck

valves positioned in the neck portion, and a piston operable in the cylinder on one side of the neck portion for operating the ball valves and neck valves for discharging the oil from the can.

2. A reversible oil can comprising an oil receiving chamber, a cover provided for said chamber, a neck portion extending downwardly through the center of said chamber and being bent at right angles, a spout secured to said neck portion and extending upwardly therefrom, V-shaped piping formed integral with the right angle portion of the neck, a stop pin arranged in said piping adjacent the right angle bend and each stop being provided with a central opening, and a ball valve arranged therein, a cylinder formed on one side of the spout portion, a plunger rod extending into said cylinder and a coil spring arranged within said cylinder and spout portion, for discharging the oil from the can.

In testimony whereof, I have affixed my signature in the presence of two witnesses.

EDWIN C. WOLFE
